UNITED STATES PATENT OFFICE

FREDERICK J. KUBLER, OF NEW YORK, N. Y., ASSIGNOR TO A. S. CAMPBELL COMPANY, OF EAST BOSTON, MASSACHUSETTS, A CORPORATION OF MASSACHUSETTS

PILLAR FOR VEHICLE BODIES

Application filed August 16, 1929. Serial No. 386,344.

This invention relates to the construction of the pillars of vehicle bodies which above the belt line are of metallic construction and of restricted dimension, and the object is to provide an improved construction for such a pillar in which the primary column portion thereof is formed of metal stampings.

My invention will be well understood by reference to the following description of an illustrative embodiment thereof shown by way of example in the accompanying drawing, wherein:—

Fig. 1 is a side elevation, as seen from the exterior of the body, of the primary column portion of the body pillar located at the cowl;

Fig. 2 is a rear elevation thereof;

Fig. 3 is a section on an enlarged scale on the line 3—3 of Fig. 2;

Fig. 4 is a section on a similar scale through the corner of the completed body on the plane of the line 4—4 of Fig. 2, the arrow being parallel to the center line of the body; and

Fig. 5 is a section on the same scale on the line 5—5 of Fig. 2.

Referring to the drawing, the pillar shown by way of example embodies a primary column portion, shown in Figs. 1 and 2, having a lower part 7 adapted to be incorporated with the framework of the body below the belt, for example, to be secured by means of screws to the rear face of the upright member of a wooden cowl frame, and an upper portion 9 extending above the belt line and here shown as inclined or raked rearwardly to provide for the installation of a slanting windshield. The contour of the pillar above the belt may be completed (see Fig. 4) by a separate member 11 conveniently in the form of an aluminum die casting detachably secured thereto as by means of screws 13 tapping into the same from the rear, as described in the application of Raymond A. Calpin, Serial No. 306,463, filed Sept. 17, 1928; now Patent No. 1,782,230, dated Nov. 18, 1930.

The member 11 may be provided with a rabbet 15 to receive the windshield 17 and a rabbet 19 receiving the overlap flange 21 of the door 23.

In accordance with my invention I form the primary column portion of the pillar, at

least in that portion thereof which extends above the belt and supports the roof, of laminated construction, and I have herein shown it as comprising two steel stampings, shaped individually to desired form and secured together, preferably by welding, one substantially doubling the other to form what might be called the backbone of the pillar of multiple thickness and strength, the laminations which go to make it up, however, being relatively small and easily shaped. Preferably the shaping of the two parts is such that they mutually reinforce one another when laminated together.

In the example shown in the drawing I utilize a rear stamping comprising a transverse web portion 25, the upper portion of which above the belt is disposed at an angle to the attaching portion below the belt, as shown in Fig. 1. The lower portion may be offset to provide a channel-like hinge pocket 27 and the upper portion, which may be narrower transversely, may be flanged rearwardly at 29 on the inner side to provide a stop for the upper portion of the door (see Fig. 4) and to reinforce the transverse web portion of the pillar as a whole. The upper end of the web may be bent rearwardly to provide an anchor 31 for attachment to the side roof rail. The pillar also embodies a forward member 33 having a transverse web portion in face to face contact with the raking portion of member 25 substantially doubling the same and secured thereto, preferably by welding. This portion extends downwardly, bridges over the angle 35 of the offset 27 which provides the hinge pocket, is welded to the back of the pocket at 37 and preferably extends, bridging the lower angle of the hinge pocket at 39, and doubles the lower portion of the member 25 with an extension 41. This arrangement effectually reinforces the portion of the pillar which would otherwise be weakened by the sharp angle formed by the offset of the hinge pocket. The construction is particularly adaptable to pillars in which the upper portion rakes, as herein shown, since the forward stamping 33 may extend substantially straight to the back of

the hinge pocket, as shown, across the angle 35.

Suitable means are provided for anchoring the pillar to the front top rail and I have herein shown an anchoring arm 43 formed of a separate piece having its ends sandwiched between the webs 25 and 33 and welded in position. The anchor 45 for attachment to the cowl bar is herein shown as similarly secured and it may be provided with a shoulder 47 adapted to engage the side of the web 27 and with an attaching portion 49 sandwiched between the two webs, the forward web 33 being suitably offset to receive it. This portion 49 may be shaped in part to overlie the back of angle 35 at the offset of the hinge pocket to stiffen the same. In the construction shown (see Fig. 1) the outer portion of web 33 extends substantially straight as a tie across the angle. At its inner portion the angle is back supported by the web through part 45 and at this inner portion the pillar at the location of the hinge pocket resists deflection through the transversely extending box sections formed at the top and bottom of the hinge pocket.

As seen in Fig. 4, I have herein shown the web portion 33 as somewhat narrower than the transverse web portion 25 to provide at the inner side a rabbet adapted to receive a flange 51 on the covering piece 11 and the outer edges of the webs may be cut away as seen at 53 (Fig. 2) to provide a seat for a parallel flange 55 constituting the rear face of the rabbet 21.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. A vehicle body pillar comprising a sheet metal web adapted to extend from the roof beyond the belt and offset adjacent the belt to provide a pocket and a second web in face to face contact with the first and secured thereto at the back of said pocket and at either side thereof and bridging the angles of said offset.

2. A vehicle body pillar comprising a stamping of web section having an attaching portion for incorporation in the framework of the vehicle below the belt and a raking upper portion, a part of the said attaching portion being offset to provide a pocket, a second stamping having a web portion doubling the raking portion of the first and attached thereto and tied across the angle of said offset part to the back thereof.

3. A vehicle body pillar comprising a stamping of web section having an attaching

portion for incorporation in the framework of the vehicle below the belt and an upper portion, a part of said attaching portion being offset to provide a pocket, a second stamping secured to the back of said pocket and to said upper portion and bridging the angle of the offset, and an arm for anchorage to an adjacent part of the vehicle frame received and secured in said angle and between the stampings.

4. A body pillar for vehicles comprising a main portion consisting of a plurality of laminations secured together in face to face contact throughout at least the major portion of their area, one lamination having a part between its ends offset toward the other lamination, said other lamination bridging an exterior angle of the offset to provide in cooperation with the first lamination a structural form, the laminations mutually interbracing one another at the location of such offset.

5. A cowl pillar for vehicle bodies comprising an upright of transverse web section having a portion for incorporation with the frame work of the vehicle below the belt and a portion rising above the belt and extending at an angle to accommodate a slanting windshield and a second member welded to said portions above and below the belt respectively and disposed differentially thereto, between such areas of attachment to provide a box section adjacent substantially at the angle of said portions to resist flexure thereat.

6. A cowl pillar for vehicle bodies comprising a portion for incorporation in the frame work of the vehicle below the belt and a portion to extend above the same slanting rearwardly from said first portion and comprising two metallic webs secured together in face to face contact throughout the major part of their areas to provide in the pillar a primary column of double thickness of metal, one web having an offset adjacent the junction of said portions and the other bridging the offset to provide a reinforcement at the angle resisting fore and aft flexure.

7. In a vehicle body a body pillar incorporated with the framework of the vehicle and defining a side of a door opening said pillar comprising a column-like body consisting of a plurality of laminations of sheet metal secured together in face to face contact throughout at least a substantial portion of their area and an anchorage arm for securing said column-like body to other portions of the framework received and held between the faces of such laminations.

In testimony whereof, I have signed my name to this specification.

FREDERICK J. KUBLER.
